UNITED STATES PATENT OFFICE.

JOHN KRULISH, OF BOISE, IDAHO.

PIPE-PULLING MACHINE.

1,031,185.

Specification of Letters Patent.

Patented July 2, 1912.

Application filed November 8, 1911. Serial No. 659,170.

To all whom it may concern:

Be it known that I, JOHN KRULISH, a citizen of the United States, residing at Boise, in the county of Ada and State of Idaho, have invented a new and useful Improvement in Pipe-Pulling Machines, of which the following is a specification.

This invention relates to a device for pulling pipes and especially to the lifting of 10 pipes employed in connection with wells.

The invention consists of the novel features of construction hereinafter set forth, pointed out in the claims and shown in the accompanying drawings, in which:

15 Figure 1 is a side elevation showing the device in position for use. Fig. 2 is a section on the line 2—2 of Fig. 1. Fig. 3 is a transverse section taken immediately above a foot operated gripping jaw. Fig. 4 is a 20 detail sectional view on the line 4—4 of Fig. 1. Fig. 5 is a detail perspective view of the upper portion of a pipe steadyng member.

In constructing the device I employ a U-shaped pipe frame 1 provided with suitable 25 transversely arranged base or foot members 2 and adjacent its bow portion with a horizontally arranged cross member 3 to which is centrally connected upon one side a vertically arranged rod 4 which extends a considerable distance above the frame 1 and 30 at its upper end carries a horizontally arranged guide member 5. To the other side of the cross member 3 is secured a segmental guide bracket 6 and also an upright bar 7, 35 the upper end of which is bent over the bow portion of the frame 1 as shown at 8. A single bolt can be employed for securing the rod 4, segment 6 and bar 7 to the cross bar 3. The bar 7 not only forms a brace for the 40 bar 3 but also forms a bearing for a pivot pin 9 upon which is mounted an operating lever 10. This lever supports links 11 and 12 arranged respectively upon opposite sides of the pin 9, and these links are loosely 45 connected to spring, pipe gripping members 13. The gripping members are formed of two parallel sections bolted together at one end, one of said sections being pivotally connected to one of the links 11 or 12, while 50 the other section has an offset end portion adapted to overlap the pivoted section. Both sections are provided with curved toothed portions 14, arranged adjacent the secured or bolted ends of the sections in 55 order that they may grip a pipe of the diameter usually employed. The frame 1 is

also provided adjacent its lower end with a cross bar 15 to which is bolted a plate 16 having a semi-circular recess 17, also toothed and which forms the fixed jaw of 60 a foot wrench. A movable jaw 18 pivoted upon the plate 16 and being adapted to cooperate with the recess 17 when it is desired to hold one pipe section against rotation while unscrewing an upper section. 65

In operation the gripping members 13 are fitted around the pipe to be pulled and the lever 10 operated in pump handle fashion. As the gripping members rise they grip the pipe and lift it a certain distance, 70 and then release the pipe and drop back and take hold and again lift a certain distance. As these members are connected to the lever 10 upon opposite sides of the pivot pin 9 it will be seen that as one gripping 75 member is falling and getting into position to take another grip upon the pipe the other member is lifting so that the upward movement of the pipe is practically continuous. As the pipe is drawn upwardly 80 the bracket 6 and guide member 5 will steady it and prevent it from swaying to one side. When a length of pipe has been lifted and it is desired to unscrew it before lifting another length the gripping members 85 are disengaged from the pipe, and by pressing against the movable jaw 18 the pipe is gripped below the length to be disconnected and held against rotation during the unscrewing of the upper section of the 90 pipe, which is of course turned with an ordinary pipe wrench. This enables one man to perform all the work of pulling a pipe and unscrewing the pipe sections as they are drawn upwardly. 95

In order that the device may be used with pipes of different diameters it will be noted that the gripping jaws 14 have their secured ends held by means of a threaded bolt 14^a, and by partially unthreading one 100 of the gripping jaws they can be spaced apart sufficiently to enable a larger pipe to be gripped. It will also be understood that when the gripping members are disengaged or unhooked in order to pass a coupler they 105 are again fitted and clamped upon the pipe below the coupler, and so held during the unscrewing of the upper section, thereby preventing the lower section from falling back into the well.

What I claim is:

A device of the kind described compris-

ing a U-shaped frame, a horizontally arranged cross member adjacent the bow portion of said frame, a vertically arranged rod connected at its lower end to the middle 5 portion of said cross member, a horizontally arranged guide carried by the upper end of said rod, a segmentally arranged guide bracket carried by the cross member and in vertical alinement with the guide carried 10 by the upper end of the rod, an upright bar having its upper end engaging the bow por-

tion of the frame and its lower end secured to the horizontal cross member, a lever pivotally mounted to the upright bar, and pipe gripping devices pivotally connected 15 to said lever upon opposite sides of its pivotal point, as and for the purpose set forth.

JOHN KRULISH.
